UNITED STATES PATENT OFFICE.

JAMES POWERS, OF NEW YORK, N. Y., ASSIGNOR, BY MESNE ASSIGNMENTS, TO POWERS ACCOUNTING MACHINE COMPANY, OF NEW YORK, N. Y., A CORPORATION OF DELAWARE.

TABULATING-MACHINE.

1,224,411.

Specification of Letters Patent.

Patented May 1, 1917.

Application filed May 22, 1912. Serial No. 698,887.

To all whom it may concern:

Be it known that I, JAMES POWERS, a citizen of the United States, residing in New York city, in the county of New York and 5 State of New York, have invented certain new and useful Improvements in Tabulating-Machines, of which the following is a specification.

My invention advances the art of perforated-card accounting, widens its field, adapts it for more general use, reduces its cost and error-ratio, and greatly reduces the number of operations and the time necessary to analyze, transcribe and separately tabulate in print, for convenient use and for comparison, pluralities of related but differing topical statements recorded in the perforations of record-card series. It relates to analyzing, transcribing and tabulating in 10 print, card-perforation records. It consists in adapting tabulating machines, with only one transit through them of a card-series, to analyze, transcribe, and separately tabulate in print a plurality of the related 15 but differing topical statements recorded in the card-series; and to do so with purely mechanical and therefore with the most reliable apparatus.

Heretofore, in this art, it has been deemed 20 necessary, in order to so analyze and tabulate card-series records, firstly; to sort the cards topically, by passing them once or repeatedly through a sorting machine; to subsequently pass each sorted group of cards 25 through a tabulating machine adapted to analyze their records and tabulate the results in dials or counters; to read off and prepare copy of said dial- or counter-records; and to have the same reproduced in 30 print.

Obviously, there is a minimum error-ratio inherent in each operation which human care cannot avoid or reduce; and thus unnecessarily multiplying the number of operations directly - proportionally multiplying the error-ratio of the final tabulation. In contrast with this complex, error-multiplying mode, my simple process and mechanical apparatus enable me to run the card-series 45 once through my machine and analyze and tabulate in print a plurality of (as illustrated, two) statements recorded therein; run it through again and tabulate as many more; and continue so to do until the analy-

sis and tabulation are complete; and this 55 without introducing additional errors into the record or the results.

In general terms, my improved apparatus constitutes a card-controlled, multiple-topic, analyzing and tabulation-printing machine 60 adapted to simultaneously analyze, transcribe and tabulate in print a plurality of (as illustrated, two) topical perforated card-series records; and comprises a card-supporting plate with a plurality of series 65 (preferably digital) of perforations corresponding and registering with record-points, (perforated and unperforated) of record-card series; record-reproducing organizations comprising movable pin-boxes, each 70 carrying a plurality of corresponding series of movable pins adapted to be stopped by unperforated and to pass through perforated record-points of cards and to reproduce, beyond said plate, the perforation- 75 records thereof,—said organizations being topically settable to different card-areas so as to simultaneously reproduce different topical statements recorded in the card-perforations; a like plurality of tabulation- 80 printing mechanisms provided with key-series corresponding with pin series and card-perforation series, preferably stock adding machines; and a like plurality of aggregations of analyzing and selecting me- 85 chanical actions adapted to co-act with record-reproducing pins, analyze the card-perforation record thereby reproduced and select and cause the operation of corresponding tabulation-printing mechanism keys and 90 the tabulation and summation in print thereby of the card,—and card-series—records.

Each analyzing and selective action comprises an analyzer adjustable in operable 95 location relatively to different card-record series and when so located adapted to be positioned by and to thereby analyze the record reproduced by an extended pin of a co-acting pin series; a (digital) series of 100 actuators or striking keys severally non-adjustably operably located relatively to keys of a key series of a tabulation-printing mechanism; a transmission; and a selector operably connected thereby with, and adapted to be positioned by, said analyzer to select 105 and cause the operation of the actuators and printing-keys corresponding with the rec-

ord-reproducing pin then co-acting with said analyzer.

The analyzers of each aggregation of actions are organized by being mounted on a movable carriage and thereby adapted to be conveniently, coactingly located relatively to corresponding pin-series of the pin boxes and record-perforation series of card-areas to be tabulated; and because the tabulators are fixed in location, and the actuators and selectors are thereby located, the transmissions must be extensible in order to permit the translation of the analyzer organizations between different card areas.

15 In the accompanying drawings showing one embodiment of my invention, Figure 1 is a general plan of a machine adapted to simultaneously analyze and tabulate in print two topical, card-perforation records.

20 Fig. 2 is a partial vertical section on the line 2—2 of Fig. 1. Fig. 3 is a transverse vertical section on the line 3—3 of Fig. 1, illustrating the relations of the record cards, record-reproducing pins, action-analyzers and transmissions. Fig. 4 is a complementary section on the line 4—4 of Fig. 1 illustrating the relations of the transmissions, selectors, actuators and tabulation-printing mechanisms and the keys thereof. Fig. 5 is

25 a corresponding, enlarged, partial plan. Fig. 6 is a vertical section on the line 6—6 of Fig. 1. Fig. 7 is an end elevation of the machine. Fig. 8 is a view like Fig. 3, but illustrating analyzers analyzing a pin-reproduced record. Fig. 9 is an enlarged partial front elevation illustrating the mode of adjustably locating the pin boxes to different card-areas and the analyzer organizations thereto. Figs. 10 to 13 inclusive are

30 details of the analyzers and their carriage, Fig. 10 being a plan, Fig. 11 a corresponding end view, Fig. 12 a side elevation, Fig. 13 an opposite end view. Fig. 14 is a side view and Fig. 15 a plan of a selector. Fig.

35 16 is a partial vertical section illustrating the pin box and the card-controlling means. Fig. 17 shows the lay-out of a record card and a statement recorded in perforations thereof. Figs. 18 and 19 illustrate means

40 for accurately positioning the analyzer carriages and analyzers relatively to card-areas and pin-boxes adjusted thereto, Fig. 18 being a plan, and Fig. 19 a section on the line 19—19 of Fig. 18.

45 In the art of card-accounting, it is common to lay out series of large cards in numerous rows and columns and thereby adapt them for recording by one perforation in each column, a large number of attributes pertaining to the objects, or the single object, to whose record individual cards are devoted; to tabulate and summarize card series as such; and also to cull out, tabulate and summarize topical statements

50 therefrom.

My work in mechanical card-accounting machines has abundantly demonstrated the superiority of purely mechanical actions over electrical, or fluid, or mixed actions for such general purposes; and I now apply purely mechanical actions to the final stages as I have heretofore to the initial and intermediate stages of such work and with a like gain in speed and reliability. Further, the size, and the number of record-series frequently occurring on record-cards enables me, in many cases, to save the cost and time necessary to sort them preparatory to topical tabulation (as has been the custom) and to simultaneously cull, tabulate and summarize two or more topical statements from a card-series while passing them once through the machine and thereby double its capacity by the addition of auxiliary parts, without at all increasing the daily operating costs or

55 greatly increasing its first cost and bulk. Hardly less important to speed, economy and the accuracy of the final results, I adapt my machines to tabulate and summarize in print, and thereby avoid the cost and the personal errors inseparable from the former practice of tabulating on dials, reading and preparing copy from them and having it printed.

In the herein-illustrated stage of my invention, I utilize stock adding machines, A and B, as summarizing and as tabulation and summary-printing mechanisms, and connect them with the record-reproducing pins 20 of the pin boxes 26 and 27, by analyzing and selective purely mechanical actions K, whose particular organization is due to and in consonance with the arrangement of said adding machines; thus quickly realizing my primary objects.

Most of the adding machines in use have a plurality of digital series of keys, each nine in number corresponding to the digits. I adapt my machine frame 2 to support a plurality of such adding machines with their keys severally in the lines of action of my actuators so that when any actuator is operated, it will strike the corresponding adding machine key, as it would be if struck by the finger of an operator. In the normal operation of an adding machine, after each number has been set up by striking keys corresponding to the digits of the number, a handle is swung and such number is caused to register on the machine and be added to the preceding number of aggregate numbers, which registering operation also has the effect of resetting those keys that are depressed.

I operably connect a power transmission member, preferably the main shaft of my apparatus, with said handle, or the shaft of the adding machine, whereby immediately upon the actuators being operated corresponding to the perforations in the card,

the adding machine is caused to register the number set up and thereafter return the keys to normal position.

I provide a main frame 2, in which I rev-
5 olably mount a main shaft 19, suitably connected with a source of power, preferably an electric motor, and bearing power-transmission elements, which include pin-box cams 17, which are slotted in cams-disks 18; retractor-, and card-picker operating cams 38, card-stop cams 31, printing cams 80 and adding-machine resetting cams 124; and suitable transmission members, illustrated as sprocket wheels, (Fig. 3) for
10 driving the card-feed rolls, which are generally designated by 30. I assume the axis of the main shaft to be the principal axis of the machine. On the transverse axis I raise the frame 2 and mount the series-per-
15 forated card-supporting plates, 28 and 29; the card hopper 44, to contain stacks of cards to be analyzed; the card picker 43, to pick cards one at a time from the bottom of the card stack and feed them to the feed
20 rolls 30; the card-stop 31, which operatively positions them for analysis; and the pin-box table or jig-frame 11^b; and opposite to the hopper, but at a lower level, the analyzed-card bins 144.
25
29 Lower than the card plates 28, 29, I provide axially-extending slide-ways for mounting my action-analyzer carriages 33, and comprising anterior, parallel V-guides 98^a, on a bed-plate 98 and a posterior track
30 47 substantially under the rear of said card-
35 plates. To the sides and anteriorly I provide elevated frame extensions for supporting the selectors and actuators of the actions and posterior lower frame extensions on
40 which I locate the adding machines A and B.
45 As illustrated, the actions K and pin-boxes 26 and 27 are divided into two groups combined respectively with adding machines A and B to form two distinct and independent analyzing and recording mechanisms, R and R'.

In each analyzing and recording mechanism, R and R' the action analyzers, 32 are organized as a movable unit and suitably
50 spaced in consonance with the series-spacing of the pins 20 of the pin boxes by mounting them on their carriage 33, which in turn is mounted on the guides 98^a and rail 47; and the pin boxes are likewise units and adjust-
55 able as such, to different card-areas; and, while the carriage 33 and pin box are independently movable, I provide exact positioning means (to be described) to make sure that when adjusted relatively to particular
60 card-areas, the several analyzers will be in the same planes with their proper pin-series.

To mount and reciprocate the pin boxes, I provide an open reciprocating jig-frame or table 11^b, built up of axially extending
65 guide bars 11 and 12 and quadrangular ver-

tical open, end guide frames 13 and 14 which engage vertical parallel guides on the machine frame 2 and on whose lower cross-bars 13^b I revolvably mount cam-rollers 15 and 16, which engage the slot-cams 17, on the main shaft 19, by which the jig frame and pin boxes are reciprocated. On each guide bar 11, 12, I provide a rack 24, for exactly positioning the pin boxes.

Each pin box comprises upper and lower fixed series-perforated pin plates 7 and 8 secured to separators 9 and 10 with their ends projecting to form therewith parallel channel guides by which the pin boxes are mounted on their ways 11 and 12 of the jig-frame, and a movable U-shaped series-perforated-setting plate 22 with down-turned ends and rack-teeth 23 thereon adapted to engage the jig-frame racks 24 to accurately position the pin boxes and secure them in adjusted positions. In the perforations of the plates 7, 8 and 22 I mount a plurality of series of record-reproducing pins 20 with exterior heads 21 by which they are normally supported on the plate 22. I provide for sliding the pin boxes on their guides 11, 12 and locking them in adjusted position by means of screws 25, axially fixed, by engaging shoulders, in the plates 22 and whose threaded shanks work in suitable tapped holes in the pin boxes. When the screws are backed out, the plate and the pins are lifted, so that the ends of the latter clear the upper card plate 28 and the pin boxes can be slid along the frame, and their rack teeth brought to engage other portions of the jig frame racks 24, whereupon the screws 25 are driven home to lower the plate 22 and the pins 20 to operative position, and position and lock the pin boxes 26, 27, in
95
100
105 adjusted position.

The pins 20 register with correspondingly arranged holes in a pair of fixed card-support plates 28 and 29 spaced to form a card-path 164^p through which record-cards may be advanced by suitable means such as feed rolls, denoted generally by 30, as shown in Fig. 3. A card is so advanced until it engages a suitable stop 31 mounted on a rock shaft 31^a and operably connected with a cam 31^c on the main shaft 19 by means of a link and lever connection 31^b (Figs. 9 and 16, dotted line Fig. 3), and thereby operated and turned to alternately clear the card-path 164^p for the passage of analyzed cards 115 and obstruct it and arrest and position cards to be analyzed therein, with their record points registering with the perforations in the two card-plates 28 and 29.
120

Subsequently in the motion-cycle the cams 125 17 lower the jig frame 11^b, pin boxes 26 and 27 and pins 20; such pins as find unperforated record points in the card are thereby arrested; but such as find perforations therein pass their ends through them and the 130

lower card plate 29, extend below the latter and there reproduce the statement recorded in the card perforations, ready for analysis by the actions K and tabulation and summation in print by the adding machines A and B. Each action K comprises an analyzer 32, adapted to co-act with and analyze a statement reproduced by extended pins 20, a transmission, T, a selector (68 . . . 73) there-
16 by connected with and positioned by the analyzer, and a digital series of actuators (48 . . . 56) severally operably located relatively to keys 58 of a key-series of an adding machine (A or B), to the selector and to an
15 operating platen 77, reciprocated by the printing cam 80.

The drawings illustrate two analyzing and recording mechanisms R and R', each including a laterally-adjustable pin box, 26 or 27, with six digital series of pins, 20; six actions, K; an action carriage 33, slidably mounted on its ways 98^a and 47 and mounting six analyzers 32 and transmission elements severally operably connected therewith, and operably locating and spacing said analyzers in vertical planes corresponding with pin-series planes; an adding machine, A or B; a pair of printing cams 80, on the main shaft 19; and a printing platen 77, 25 116, each operably connected with a pair of said cams 80 and operably located relatively to the selecting ends of a group of selectors (68 . . . 73, or 115) and the co-acting ends of a like group of actuators (48 . . . 56, or 117)
30 35 and adapted, when elevated, to lift the plungers, 74, of advanced selectors and the ends of actuators co-acting therewith and depress and strike adding machine keys 58, with the outer ends of such actuators. Each analyzer 40 32 has an upstanding analyzing finger 34, and the carriage 33 is so arranged that when advanced the finger 34 will be adjacent to the bottom of the card plate 29 opposite one series of perforations, through which pins of 45 one set may pass. The analyzer finger is normally held just anterior to the pins, as indicated in Fig. 3, and when advanced will be arrested by engaging a pin which, by the lowering of the pin box, has been ad-
50 vanced through a perforation in a card properly located on the card plate 29. Since but one hole is made in each digital record series of the card in recording a statement, in pin-reproducing it only one pin of 55 each pin series can be advanced below the card-plate 29, to co-act in analysis with its analyzer 32, by arresting the advance of and positioning the latter. In co-acting series where the card contains no perforation, the
60 pin has no statement to reproduce, and is not advanced to co-acting position; and its analyzer advances to its limit and causes the tabulating mechanism to print a naught, or not at all when the naught, if printed,
65 would occur on the left hand of the number

printed. The analyzers 32 and selectors 68 . . . 73 are spring-advanced by a spring connected with the latter; and their advance is timed and they are all retracted by a common retractor, F; all as hereinafter set forth. Fig. 8 illustrates an analysis in process, with analyzers advanced, five co-acting with and positioned by record-reproducing pins, and one advanced to its limit.

The action carriage 33 is best illustrated in Figs. 10 to 13. Its web is a bar Z-like in shape; it has a lower anterior foot 87, in which are formed the parallel guides 87^a by which it is mounted and guided on the fixed guides 98^a of the web-plate 98; a posterior steadyng roller, 45, which runs on the track 47; and two slotted analyzer-carrying heads, 33^a in which I form guide slots 33^b which contain, locate and guide the analyzers 32. The exact positioning means which insures correct alinement of the carriage and its analyzers with a co-acting pin box and its pin-series comprises (Figs. 18 and 19) a series of conical sockets, 105, sunk in the bed-plate 98 and corresponding with the teeth 90 of the jig-frame racks 24, which position the pin boxes; and a spring-advanced plunger 104, which plays in a properly located bore formed adjacently in the foot 87 of the carriage and whose conical head 104^a engages 95 and fits the sockets 105. The obliquity of said head and sockets is such that the plunger head will chatter over the sockets while the carriage is being shifted, but as it approaches its desired position and its motion 100 is slowed, the head 104^a will engage a socket 105 and thereby enable the operator, by feeling such engagement, to exactly locate the carriage.

On the carriage foot 87 I mount the 105 power-receiving members of the transmission T (which are operably connected with the analyzers) to that end providing in its upper face a series of slots 88 substantially severally in the same planes with the analyzer slots 33^b in the carriage heads 33^a; a series of axial bores 85, transverse to and communicating with said slots 88 for the transmission shafts; and two axial bores, 100 and 101, respectively, threaded for engagement with the carriage's feed screw 106 and made larger for the clear passage of a like feed-screw, 102, which is in engagement with the action carriage 41 of the other analyzing and recording mechanism R'. 110 115 120

The feed-screws 106 and 102 are revolvably mounted but axially fixed in the frame 2 and are each provided with a hand-crank 107, and 103, by which they can be turned to shift the action carriages 33 and 41. 125

Fig. 4 is a sectional side elevation illustrating the digital series of actuators (48 . . . 56) of an action K (like in number to the pin-, and adding-machine-key series), their mode of coaction with the selec- 130

tors (68 . . . 73), the selectors, the transmission members connected therewith, and the mode of mounting the platen 77 by its end posts 77^a and cam roller 79 in its parallel guides, 78 and reciprocating it by the cams 80.

Each actuator consists in a lever provided with a posterior striking head adapted to contact with and operate an adding machine key 58, and a pendant key-rod (designated in series 59 . . . 67) pivoted on its anterior end and adapted to coact with the selector plunger 74; and is medially pivoted on a pivot rod 57, common to like keys of all the actions of the mechanism (R or R'). The pivot rods 57 are graduated in their locations correspondingly with the length of their actuators pivoted on them and with the positions of the adding machine keys 58, so that one ratio is maintained between all the posterior and anterior actuator lever-arms and the unvarying stroke of the platen 77 will cause equal motions of the striking heads of the actuators.

The actuators are properly spaced on the rods 57 by separators; and to economize space, as best shown in Figs. 1, 2 and 9, their pendant key-rods (59 . . . 67) of each series are in one vertical, transverse plane and they are alternately staggered on opposite sides thereof, and tapered from their pivots, that they will not interfere. The pendant rods are equally spaced and guided in registering holes bored in an upper guide plate 81^a and a lower guide and positioning plate 81^b; fixed on each pendant is a collar 81^c; and a spring 81 strained between said collar and the upper guide plate 81^a retracts the actuator and normally positions it with said collar in contact with the positioning plate 81^b and its striking head retired from the adding machine key 58.

I mount the selectors of each mechanism R, R', in slots formed in auxiliary axially-extending plane members 268, and severally in the same vertical planes with series of actuators and their pendants. Each selector 68 . . . 73 is preferably a rectangular bar advanceable by a spring 82 strained between a lug 83 on the selector and a fixed abutment 84, and having a vertical guide bore in its posterior head and mounted therein a vertically-acting plunger 74 with a lower head 75 pressed against the platen 77 by a spring 76, strained between said head and the selector.

When the platen is elevated, it lifts all of the selector plungers and that actuator if any, of each each action K beneath whose pendant a selector plunger is located. The analyzer and selector of each action are connected, angularly fixed and synchronized relatively to one another, but axially adjustable by an independent transmission T which is practically a forked rocking lever

with an extensible pivot or rock shaft, an axially fixed arm (the driven arm 95 connected with the selector) and an axially shiftable arm (the driving arm 88 connected with the analyzer).

In final analysis the analyzing and selecting organization comprising the analyzer, transmission and selector, constitute in and of themselves a subordinate action included in that designated by K and are best described as constituting a forked rocking lever with flexibly-connected arm extensions (the analyzer and selector); and, to adapt it to coact with differently located pin-series, provided with an extensible axis. It is obvious that this sub-action would be operable (but not adjustable to different pin-locations) if made integral with slight structural but no functional modifications, and if made with its pivot shaft in two slidably-engaged sections each integral with an arm, and modified as aforesaid, it would possess all the functions it now does.

A parallel-sided socket 90 is formed on the analyzer 32 and a similar socket 97, on the selector. The driving arm 88' is located in a slot 88 of the carriage-foot 87 and fixed to a telescopic, extensible shaft 86, by means of a bearing sleeve 86^a rockably mounted but axially fixed in one of the bores 85 in said foot. The driven arm 95 which engages the selector, is fixed on a revolvably mounted, but axially fixed section 91 of the transmission shaft, coaxial with and adapted to telescope the section 86 connected with the carriage, and mounted in the main frame 2 by means of shouldered sleeves 93 and 94. The shaft sections are illustrated as square tubes, but any sliding engagement would be effective.

I provide flexible connections between the driving and driven transmission arms 88', 95 and the analyzers and selectors, consisting of cylindrical or rounded heads respectively, 89 and 96 on said arms and sockets 90, 97 on the analyzers and selectors respectively. This mode of connecting constitutes the transmission, a forked lever with flexible members, and causes the spring 82 to tend to advance the analyzers and selectors synchronously to their limits.

In each mechanism, R and R', the six transmission shafts are parallel and as closely spaced as practicable; the driving arms 88' are correspondingly stepped in their slots 88; and the sockets 90 and 97 of the analyzers and selectors respectively are correspondingly stepped, so that when retracted or extended said arms are all parallel as illustrated in Figs. 3, 4 and 6, and the selector plungers and analyzer fingers 34 are respectively alined.

The retractor F, during its retraction, times the advance of the analyzers and selectors until the former are arrested by 130

6 pins 20, limits the advance of such as are not so arrested, and during its advance retracts them all, picking up such analyzers as are pin-positioned. The retractor F is 5 a rocking open frame pivotally mounted on the machine frame 2 parallel to the shaft 19 and comprises a pair of end mounting bars 35, exterior to the outer card-plate perforation series, a retracting bar 39 in the 10 free ends of said arms and adapted to contact with the posterior ends of the analyzers 32 and retract them and the selectors 68 . . . 73; and a lower rod 42* on which I pivot one end of a link 42, the opposite end of 15 which is pin-connected with the sliding card-feed or picket 43, to operate it. The retractor F is rocked by a pair of cams 38 on the main shaft 19, being operably connected therewith by a pair of slotted links 20 36, each pivotally connected with a retractor mounting-arm 35; provided with a slot 36* which envelops the shaft 19 and by the engagement of its sides therewith, transversely 25 positions itself and guides its own reciprocation; and with a revolvably mounted roller 37 which engages a cam 38.

The springs 82 tend to advance the selectors 68 and analyzers 32 to their limit. But their advance is controlled by the retractor F. The cams 38 will advance the retractor, retract all the analyzers 32 and selectors and so hold them with the fingers 34 anterior to the pins 20 (Fig. 3), the selector plungers 74 anterior to the actuator 30 pendants, 59 . . . 64 (Fig. 4) and the springs 35 82 fully strained. Upon a card being inserted and a pin box advanced to cause some of the pins to project through the card and below the supporting plate, the said cams 40 will retract the retractor and permit the springs to advance the selectors and analyzers synchronously with the retraction of the retractor until certain analyzers and their connected selectors are arrested and positioned by record-reproducing pins and the 45 remainder have followed the retractor to the limit of its retraction; whereupon the cams 80 will raise the platen 77 and the positioned spring plungers carried by the selectors will 50 be elevated to engage the pendant rods on the actuators, and swing the latter to engage the keys of the adding machine.

The above description and reference characters generally apply to the analyzing and 55 recording mechanism R. Its mate, R', is similar, but reversed, relatively to the transverse axis; its members correspond with and have like functions to those of the mechanism R and are indicated on the drawings by 60 reference characters as follows; its carriage 41; analyzers 40 and transmission therewith; arms 111 connected therewith; selectors 115 and driven transmission arms 114 and connected selector plungers 115'; actuators 117 65 and their pendant rods 118; and platen 116

and its cams are exactly like those of the mechanism R, respectively designated 38, 32, 88', 68 . . . 73, 74, 48 . . . 56, 59 . . . 67, and 77; its feed screw 102 and its handle 103 are like those 108 and 107 but the handle 70 is at the opposite end of the machine; the permanently located transmission shaft sections 113 are on the opposite side from those 91, and the shaft sections 112 connected with the carriage 41 extend oppositely to 75 those 86.

This organization of the analyzing and recording mechanisms gives them the widest possible range of settings relatively to different record-card areas, because one mechanism, as R, may be located at the outer limit of its range and the other, R', located in juxtaposition to the former, thus enabling my apparatus as herein illustrated, to simultaneously cull out, analyze and record in 85 print any two statements properly recorded in perforations of a card, however those statements may be located thereon.

Means are also provided for connecting the main shaft 19 with the handle or an operating member of each adding machine to cause the latter to register immediately after 90 its keys have been struck by the actuators.

The shaft of the adding machine, as indicated at 120, in Fig. 7, carries a gear 121 meshing with a slidable rack 122. On the latter is a roller 123 bearing on a cam 124 fast on the shaft 19. This cam is properly timed to advance the rack immediately after the actuators have struck whereby the shaft 100 120 of the adding machine will be rotated and cause the machine to register and reset its keys in the usual manner.

The cam roller 125 of the rack 122 is held in contact with the cam 124 by a spring, 105 which is preferably that usual in adding machines, to retract the shaft 120 thereof.

The operation of my apparatus is as follows:

As illustrated in Fig. 17, a standard record-card lay-out comprises a plurality of (digital) series of record points and a plurality of facts pertaining to one object are recorded by making one perforation suitably located in some or all of said series. 110 115

It is desired to cull out, analyze and record and summarize in print one, or it may be two, topical statements from a series of such cards.

The cards are stacked in the card hopper 120 44; the jig frames 113 and pin boxes 26 and 27 are raised (by their cams 17) and the screws 25 are backed out, which lifts the plates 22 and the pins 20 clear of the card plates 29, 28 and the positioning teeth 23 125 of the plates 22 clear of the racks 24; the pin boxes are shifted to coacting positions relatively to record card areas whose record points are used to designate facts of the said topics, and the screws 25 are set, which 130

causes the positioning rack teeth aforesaid to mesh and exactly position and lock the pin boxes where they should be.

The carriages 33, 41, are then correspondingly adjusted, being accurately set by the engagement of the positioning pin-heads 104^a with sockets 105 in the bed plate 98. The revolution of the main shaft and the transmission members thereon, reciprocates the jig frame 11¹, pin boxes 26, 27 and pins 20, and the platens 77 and 116; rocks the retractor F, thereby retracting, and permitting the spring-actuated advance of the analyzers and selectors and reciprocating the card picker 43; rocks the card-stop 31; and operates the card feed 30.

The functionings of the cams are so timed that during the rise of the pin boxes (by which the card-path is cleared of pins), the 20 card-stop is set, the card-picker and card feed pick a card from the hopper and advance it to operative position (fixed by the card stop) the analyzers and retractors are retracted, the platens rest in their lowest positions, the actuators are retracted and the adding machine keys are extended, all becoming ready to perform their functions.

When the pin boxes descend, the points of the pins of their digital series register with 30 corresponding points in the digital card series; those pins which find no record perforations in the card are arrested; but those which find such perforations extend their ends through the holes in the card support plate 29 and reproduce, below the plate, the statement recorded in the card perforations.

Immediately thereafter the retractor F is retracted, thereby permitting spring-actuated advance of the analyzers and selectors 40 and also retracting the card-picker 43. Those analyzers which find no pins 20 in their paths advance with the retractor to the limit of its motion and their connected selectors advance with them to zero position; 45 but those analyzers which find and are arrested by pins, severally arrest their connected selectors with the plungers thereof in selected positions which reproduce the card-record, each recording selector plunger being 50 then beneath a pendant rod of an actuator of the series with which it coacts.

The platens 77, 116 are then lifted by their cams 80 and lift the selector plungers and such actuator pendants as register with selector plungers and swing the connected actuators; which strike and depress, and set their adding-machine keys, ready to reproduce in print, in and by the adding machines, the statements culled from the card record. At such times non-registering selector-plungers and actuator pendants respectively move idly and remain at rest; and adding machine keys corresponding with the latter remain extended and cause no record.

65 Following the above described operations,

the platen is lowered, the just-operated actuators and their key rods are spring-retracted, the shaft 120 of the adding machine is operated to cause it to print said record and extend its keys, the card stop is retired, 70 opening the card-path, the card feed 30 advances the analyzed card from the card-path to the analyzed card-bin, the card-stop is again set to close the cardway, the retractor is advanced, retracts the analyzers and selectors, fully strains the spring 82 of the latter and advances the card picker and another card, for another cycle of operations; and so continues until the power supply is suspended.

Having thus described my invention, I claim:—

1. A tabulation-printing card-accounting machine of the type in which movable pins coact with record-card perforations to reproduce statements thereby recorded and comprising movable pins arranged in series adapted to be shifted to different record-point series of record cards and to coact with and reproduce statements recorded in perforations of such card-series, tabulation-printing mechanism adapted to print such statements in tabular form, and a purely mechanical action adapted to be operably located relatively to the locations, as aforesaid of said pin-series and to connect record-reproducing pins thereof with said tabulation-printing mechanism and cause its operation and the printing thereby of statements reproduced by said pins.

2. A tabulation-printing, card-accounting machine of the type in which movable pins coact with record-card perforations to reproduce statements thereby recorded and comprising movable pins arranged in a plurality of series, pin-series adapted to be independently shifted to coact with different record-point series of record cards and to simultaneously and independently reproduce statements recorded in perforations of the different card-series with which said pin series coact, a plurality of tabulation-printing mechanisms adapted to print such statements in tabular form, and a plurality of purely mechanical actions each adapted to independently connect one of said pin-series with a tabulation-printing mechanism and cause its operation and the printing thereby of statements reproduced by pins of the pin series with which it is connected by said action.

3. A tabulation-printing, card-accounting machine of the type in which movable pins coact with record-card perforations to reproduce statements thereby recorded and comprising movable pins arranged in a plurality of series, pin-series adapted to be independently shifted to coact with different record-point series of record cards and to simultaneously and independently repro-

form, a purely mechanical action adapted to be operably located relatively to the locations as aforesaid of said pin-series, and to connect record-reproducing pins thereof 5 with said tabulation-printing mechanism and cause its operation and the printing thereby of statements reproduced by said pins, and positioning means connected with said jig-frame and pin box and adapted to 10 accurately position the latter, and positioning means operably connected with said action and adapted to accurately position it relatively to said pin series.

8. A tabulation-printing, card-accounting 15 machine of the type in which movable pins coat with record-card perforations to reproduce statements thereby recorded and comprising a series of movable pins adapted to coat with and reproduce statements 20 recorded in card perforations, tabulation-printing mechanism adapted to print such statements in tabular form, keys of said mechanism operable to cause items of such statements to be printed, an analyzing and 25 selecting mechanical action adapted to connect record-reproducing pins of said pin-series with said tabulation-printing mechanism and cause its operation and the printing thereby of statements reproduced by 30 said pins, said action comprising an angularly-movable member adapted to be positioned by record reproducing pins and to cause the selection and operation of keys of and the printing by said tabulation printing 35 mechanism of record items reproduced by said pins.

9. A tabulation-printing, card-accounting machine of the type in which movable pins coat with record-card perforations to reproduce statements thereby recorded and comprising a series of movable pins adapted to coat with and reproduce statements recorded in card perforations, tabulation-printing mechanism adapted to print such 45 statements in tabular form, keys of said mechanism operable to cause items of such statements to be printed, an analyzing and selecting mechanical action adapted to connect record-reproducing pins of said pin-series with said tabulation-printing mechanism and cause its operation and the printing thereby of statements reproduced by said pins, said action comprising a movable member adapted to be positioned by record 50 reproducing pins and to cause the selection and operation of keys of and the printing by said tabulation printing mechanism of record items reproduced by said pins.

10. A tabulation-printing, card-accounting 55 machine of the type in which movable pins coat with record-card perforations to reproduce statements thereby recorded and comprising movable pins arranged in series adapted to be shifted to different record-point series of record cards and to coat

with and reproduce statements recorded in perforations of such card-series, tabulation-printing mechanism adapted to print such statements in tabular form, keys of said mechanism adapted to cause items of such statements to be printed, an analyzing and selecting mechanical action adapted to be operatively located relatively to the locations, as aforesaid, of said pin-series and to connect record-reproducing pins thereof 70 with said tabulation-printing mechanism and cause its operation and the printing thereby of statements reproduced by said pins, said action comprising an angularly movable, axially extensible member adapted to be adjusted to connect said pin-series and tabulation-printing mechanism and to be positioned by a record-reproducing pin and to cause the selection and operation of keys of and the printing by said tabulation-printing mechanism of record items reproduced by said pins.

11. In a tabulation-printing, card-accounting machine of the class described, an analyzing and selecting action adapted to 90 connect movable record-reproducing pins of a pin series with corresponding keys of a corresponding key-series of a tabulation-printing mechanism and cause it to print record items so reproduced and comprising 95 a series of actuators corresponding with such pin and key series, and an angularly movable member adapted to be positioned by record reproducing pins and to cause the selection and operation of keys of and the 100 printing by such tabulation-printing mechanism of record items reproduced by such pins.

12. A machine for operating a calculator from record members, comprising a support 105 for a record member, a plurality of sets of controlling members arranged to engage a record member on the support, a plurality of sets of actuators corresponding to the controlling members respectively for operating the calculator keys, means connecting the controlling members with the actuators and arranged to effect the operation of the actuators according to the records on the members that coöperate with the controlling 110 means, means for advancing the record members successively into the said support, means successively operating the controlling members and the actuators as each record is advanced by said means, and means for actuating the registering member of the calculator after each operation of the actuators.

13. A machine for operating a calculator from record members, comprising a support 125 for a perforated record card, a plurality of sets of controlling pin members arranged to engage a perforated record card on the support, a plurality of sets of actuators corresponding to the controlling members respectively for operating the calculator keys, 130

means connecting the controlling members with the actuators and arranged to effect the operation of the actuators according to the perforations on the cards that coöperate with the controlling pins, means for advancing the record card successively into the said support, means for successively operating the controlling members and the actuators as each record is advanced by said means, and means for actuating the registering member of the calculator after each operation of the actuators.

14. In a machine for operating a calculator, the combination of a support for record cards, a plurality of sets of controlling pin members arranged to engage a perforated card on the support, a plurality of selectors one connected with each set of controlling pin members, and a plurality of sets of actuators, each set coöperating with one of the selectors whereby the selectors when advanced after being positioned by the pin members coöperating with a perforated record card will effect the operation of the actuators.

15. In a machine for operating the keys of a calculator, the combination of a support having perforations therein for receiving a perforated record card, a plurality of sets of controlling pin members, means for advancing the pin members relative to the card support to cause the pins to enter the perforations in the record card, a plurality of sets of actuators corresponding to the controlling members respectively, a plurality of selectors one for each of the sets of controlling pins, means whereby each selector is advanced from a pin member to a different position according to the pin member advanced in that set, each set of actuators being positioned in the path of movement of one of the selector plungers whereby in the said different positions to which the plunger is advanced it can coöperate with a different actuator, and means for shifting the plunger to effect the operation of the actuator with which it is positioned to coöperate.

16. In a machine for operating corresponding actuators.

17. In a machine for operating a calculator, the combination of a support for record members, a plurality of sets of controlling members arranged to engage a record member on the support, a plurality of selectors one arranged to connect with each set of controlling members to be positioned therefrom, a plunger on each selector, and a plurality of sets of actuators, each set arranged to coöperate with one of the selector members whereby the selectors and plunger when advanced after being positioned by the controlling means coöperating with a record member, will effect the operation of the actuators.

18. In a machine for operating the keys of a calculator, the combination of a support having perforations therein for receiving a perforated record card, a plurality of sets

of controlling pin members, means for advancing the pin members relative to the card support to cause the pins to enter the perforations in the record card, a plurality of sets of actuators corresponding to the controlling members respectively, a plunger on each actuator, a plurality of selectors one for each of the sets of controlling pins, means whereby each selector is advanced from a pin member to a different position according to the pin member advanced in that set, each set of actuators being positioned in the path of movement of one of the selector plungers whereby in the said different positions to which the plunger is advanced it can coöperate with a different actuator, and means for shifting the plunger to effect the operation of the actuator with which it is positioned to coöperate.

19. A machine for operating a calculator from a record member, comprising a support for a record card, a pin-box arranged to engage a perforated card on the carriage, a support, a set of analyzers movable on said carriage to engage advanced pin members, a set of shafts mounted on and axially shiftable with said carriage, a set of arms one on each shaft and engaging the analyzers respectively, a corresponding set of axially fixed shafts each having a sliding engagement with one of said axially shiftable shafts permitting relative endwise movement but causing the shafts to rotate together, a plurality of sets of actuators, and means connecting the actuators of each set with one of said axially fixed shafts to cause the operation of the actuators according to the position of the analyzers advanced to engage pins of the pin-box.

20. A machine for operating a calculator from a record card, comprising a support for the record card, a pin-box arranged to engage a card on the support and advance the pins through its perforations, a set of analyzers each movable to engage an advanced pin, a set of selectors connected with the analyzers respectively for simultaneous movement, a plunger carried by each selector, a plurality of sets of actuators and rods severally connected therewith, each set arranged to be engaged by the plunger of one of the selectors when advanced, and means for advancing selector plungers to select and engage rods of said actuator sets and cause the operation of the connected actuators.

21. A machine for operating a calculator from record members comprising a pin-box, means for advancing the pins through perforated records, a set of analyzers, resilient means for advancing the analyzers to engage pins advanced through the card perforations, a set of actuators corresponding respectively with the pins, means connecting the analyzers with the actuators where-

5 by the actuators will be operated according to the pins advanced and engaged by the analyzers and means for retracting the analyzers to tension the springs, and to release them to be advanced by the springs to engage the advanced pins.

21. A machine for operating a calculator from record cards, comprising a movable pin-box, a support for cards, means for advancing the pins through perforated cards on the support, a carriage, a set of analyzers on the carriage, means for advancing the analyzers on the carriage to engage pins advanced through card perforations, a set 10 of actuators corresponding respectively with the pins, means connecting the analyzers with the actuators whereby the actuators will be operated according to advanced pins engaged by the analyzers, means for shifting the carriage and analyzers to engage different pin-series when advanced on the carriage, said connecting means between the analyzers and the actuators being arranged to cause the analyzers in the different positions to which moved by the carriage to effect the operation of the same actuators respectively.

22. A machine for operating a calculator from record cards, comprising a movable pin-box, a support for cards, means for advancing the pins through perforated cards on the support, a carriage, a set of analyzers on the carriage, means for advancing the analyzers on the carriage to engage pins advanced through card perforations, a set 35 of actuators corresponding respectively with the pins, means connecting the analyzers with the actuators whereby the actuators will be operated according to advanced pins engaged by the analyzers, means for shifting the carriage and analyzers to engage different pin-series when advanced on the carriage, said connecting means between the analyzers and the actuators being arranged to cause the analyzers in the different positions to which moved by the carriage to effect the operation of the same actuators respectively, the pin-boxes being shiftable corresponding with the shifting movement of the carriage and analyzers to engage different sets of perforations in the card.

23. A machine for operating a calculator from record cards, comprising a movable pin-box, a support for cards, means for advancing the pins through perforated cards, a carriage, a set of analyzers on the carriage, means for advancing the analyzers on the carriage to engage pins advanced through card perforations, a set of actuators corresponding respectively with the pins, means connecting the analyzers with the actuators whereby the actuators will be operated according to advanced pins engaged by the analyzers, means for shifting the carriage

and analyzers to engage different pins when advanced on the carriage, said connecting means between the analyzers and the actuators being arranged to cause the analyzers in the different positions to which moved by the carriage to effect the operation of the same actuators respectively, the carriage having a threaded bore, and a threaded shaft engaging said bore, the shaft being supported to prevent endwise movement whereby to advance the carriage when the shaft is turned.

24. A machine for operating a calculator having keys and a register from record members, comprising a support for a record card, a plurality of sets of controlling members arranged to engage a card on the support, a plurality of selectors one for each set of controlling members and which are arranged to be advanced to different positions from the different controlling members respectively, a plurality of sets of actuators corresponding with the sets of controlling members, each set of actuators coöperating with one of the selectors respectively, and means for causing the operation of the actuators from the advanced selectors when positioned corresponding to the controlling members engaged by a record card on the support.

25. A machine for operating a calculator having keys and a register from record members, comprising a support for a record card, a plurality of sets of controlling members arranged to engage a card on the support, a plurality of selectors one for each set of controlling members and which are arranged to be advanced to different positions from the different controlling members respectively, a plurality of sets of actuators corresponding with the sets of controlling members, each set of actuators coöperating with one of the selectors respectively, and a plunger on each selector for causing the operation of the actuators from the selector.

26. A machine for operating a calculator having keys and a register from record members, comprising a support for a record card, controlling members arranged to engage a card on the support, a set of actuators corresponding to the controlling members respectively for depressing the calculator keys, mechanically operative mechanism positively connecting said controlling members with the actuators and arranged to effect the movement of the actuators according to the record on the card that is engaged by the controlling members, the controlling members being shiftable relative to the support to engage with different sets of records on a card, said connecting mechanism being constructed and arranged for adjustment corresponding to the shifting movement of the controlling members to cause the controlling members in the said different positions

of adjustment to coöperate with the same actuators respectively.

27. A machine for operating a calculator having keys and a register from record members, comprising a support for a record card, a movable pin-box, means for moving the pins through the perforated cards on the support, a set of actuators corresponding to the pins respectively for depressing the calculator keys, mechanically operative mechanism positively connecting said pins with the actuator and arranged to effect the movement of the actuators according to the record on the card that is engaged by the pins, the pin-box being shiftable relative to the support to engage with different sets of records on a card, said connecting mechanism being constructed and arranged for adjustment corresponding to the shifting movement of the pin-box to cause the controlling members in the said different positions of adjustment to coöperate with the same actuators respectively.

28. A machine for operating a calculator having keys and a register from record members, comprising a support for a record card, a plurality of sets of controlling members arranged to engage a card on the support, a plurality of selector members, one for each set of controlling members and which are arranged to be advanced to different positions from the different controlling members respectively, a plurality of sets of actuators corresponding with the sets of controlling members, each set of actuators co-operating with one of the selector members respectively, means for causing the operation of the actuators from the advanced selector member when positioned corresponding to the controlling members engaged by a record card, said selector members being adjustable relative to the card support to co-operate through the controlling members with different records on the card on the support, and to coöperate with the same actuators respectively in the different positions of adjustment.

29. A machine for operating a calculator having keys and a register from record members, comprising a support for a record card, a movable pin-box carrying a plurality of sets of pins arranged to engage a card on the support, a plurality of selector members one for each set of pins and which are arranged to be advanced to different positions from the different pins respectively, a plurality of sets of actuators corresponding with the sets of pins, each set of actuators coöperating with one of the selector members respectively, means for causing the operation of the actuators from the advanced selector member when positioned corresponding to the pins engaged by a record card, the pin-box being adjustable relative to the card support, said selector members

being similarly adjustable to coöperate through the pins with different records on the card on the support, and to coöperate with the same actuators respectively in the different positions of adjustment.

30. A machine for operating a calculator having keys and a register from record members, comprising a support for a record card, a plurality of sets of controlling members arranged to engage a card on the support, a plurality of selectors, one for each set of controlling members and which are arranged to be advanced to different positions from the different controlling members respectively, a plurality of sets of actuators corresponding with the sets of controlling members, each set of actuators coöperating with one of the selectors respectively, a plunger on each selector for causing the operation when advanced of the actuators from the selector when positioned corresponding to the controlling members engaged by a record card, and a shiftable platen arranged to engage and advance all of the plungers in any of the positions to which the selectors are advanced to correspond with the controlling members engaged by a record card on the support.

31. In a tabulation-print, card-accounting machine of the class described, a plurality of spring advanced analyzing and recording actions each adapted to be, when so advanced, positioned by record-reproducing pins and to select and cause the operation of a key of a tabulation-printing mechanism key-series and a retractor operably connected with a power transmission member and adapted to time the advance of said actions until so pin-positioned and to limit the advance of actions not so positioned and to retract and time the retraction of all said actions.

32. In a tabulation-printing, card-accounting machine of the class described, an analyzing and selecting action adapted to connect movable record-reproducing pins of differently-located pin series with corresponding keys of a tabulation-printing mechanism key series corresponding with such pin series and cause such mechanism to print record items so reproduced and comprising a series of actuators corresponding to such pin and key series and an angularly-movable, axially-extensible member adapted to be positioned by record reproducing pins and to cause the selection and operation of keys of and the printing by such tabulation-printing mechanism of record items reproduced by such pins.

33. In a tabulation-printing, card-accounting machine of the class described, an analyzing and selecting action adapted to connect movable record-reproducing pins of differently-located pin series with corresponding keys of a tabulation-printing mecha-

nism key series corresponding with such pin series and cause such mechanism to print record items so reproduced and comprising a series of actuators corresponding to such 5 pin and key series and a movable, axially-extensible member adapted to be positioned by record reproducing pins and to cause the selection and operation of keys of and printing by such tabulation-printing mechanism 10 of record items reproduced by such pins.

34. A tabulation-printing card-accounting machine of the type in which movable pins coact with record-card perforations to reproduce statements thereby recorded and 15 comprising movable pins arranged in series adapted to be shifted to different record-point series of record cards and to coact with and reproduce statements recorded in perforations of such card-series, tabulation- 20 printing mechanism adapted to print such statements in tabular form, and means adapted to be operably located relatively to the locations, as aforesaid, of said pin-series and to connect record-reproducing pins 25 thereof with said tabulation-printing mechanism and cause its operation and the print-

ing thereby of statements reproduced by said pins.

35. A tabulation-printing, card accounting machine of the type in which movable pins coact with record-card perforations to reproduce statements thereby recorded and comprising movable pins arranged in a plurality of series, pin-series adapted to be independently shifted to coact with different 30 record-point series of record cards and to simultaneously and independently reproduce statements recorded in perforations of the different card-series with which said pin series coact, a plurality of tabulation-printing 35 mechanisms adapted to print such statements in tabular form, and means each adapted to independently connect one of said pin-series with a tabulation-printing mechanism and cause its operation and the 40 printing thereby of statements reproduced by pins of the pin series with which it is connected by said action.
